DESIGN FOR MACARONI

Angelo Ronzoni, New York, N. Y.

Application August 30, 1933. Serial No. 49,168

Term of patent 3½ years

To all whom it may concern:

Be it known that I, ANGELO RONZONI, a citizen of the United States, residing at New York, in the county of Queens, and State of New York, have invented a new, original, and ornamental Design for a Macaroni, of which the following is a specification, reference being had to the accompanying drawing, forming part thereof.

Fig. 1 is a side elevation of the macaroni taken along the line 1—1 of Fig. 3.

Fig. 2 is a top view of the macaroni.

Fig. 3 is a bottom view of the macaroni, and Fig. 4 is a side elevation of the macaroni taken along the line 4—4 of Fig. 3.

I claim:

The ornamental design for a macaroni, as shown.

ANGELO RONZONI.
